UNITED STATES PATENT OFFICE.

ERNEST L. TEICH, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

KNOB OR HANDLE LOCK.

Application filed August 4, 1925. Serial No. 48,040.

My invention relates to locks and has special reference to knob or handle locks.

An object of the invention is to provide a novel and improved lock of this character.

Another object of the invention is to provide a lock of this character which is simple and durable in construction, and which may be easily applied, and in which the parts thereof may be easily assembled in proper position.

The several features of the invention, whereby the above mentioned and other objects may be attained, will be clearly understood from the following description and accompanying drawings, in which,

Fig. 1 is a front elevation of my improved lock, shown applied to a cabinet door having a three point latching device with the parts thereof shown in latched position;

Fig. 2 is a sectional view, partly in elevation taken on the line 2-2 of Fig. 1;

Fig. 3 is a rear elevation of the portion of the door illustrated in Fig. 1, but showing the parts of the latching device in unlatched position;

Fig. 4 is a transverse sectional view taken on the line 4-4 of Fig. 2;

Fig. 5 is a detail view in perspective of a locking pin or bolt forming a component part of my improved lock;

Figs. 6 and 7 are sectional views on an enlarged scale, taken on the lines 6-6 and 7-7 of Fig. 2, respectively, showing component parts of the lock in locked position; and

Fig. 8 is a sectional elevation taken on the line 8-8 of Fig. 2, showing the bolt in unlocked position.

My improved lock is shown applied to a cabinet door 2 having a three point latching device of a common construction. As shown, this three point latching device is provided with a rotatable hub 4 having a laterally projecting lug or latch bolt 6, and latch bolts 8 that are in the form of flat rods having their inner ends pivotally connected with ears on the hub 4 and their upper ends extending through and guided by straps 10 secured adjacent the upper and lower edges of the door. With this type of three point latching device, upon turning the hub 4 in one direction, the latch bolt 6 may be swung beyond the longitudinal edge of the door and the latch bolts 8 projected beyond the upper

and lower edges of the door, as shown in Fig. 1, and upon turning the hub 4 in the opposite direction, the three latch bolts may be retracted, as shown in Fig. 3.

As shown, my improved lock is provided with a rose or escutcheon 12 which, when used in connection with a three point latching device as above described, is secured by screws 13 on the front side of the door opposite the hub 4, and is further provided with a knob or handle 14 having a cylindrical shank that extends through and is mounted for turning movement in the rose 12. The inner end of the handle shank is provided with a reduced portion 15 forming a shoulder 16 that is arranged adjacent a shoulder 17 on the outer face of the rose. The rear end of the shank is provided with a rearwardly extending spindle 18 which is square in cross-section and extends through a clearance opening in the cabinet door 2. The hub 4 of the three point latching device is mounted on this spindle and is held thereon by a spring washer and nut 19 which holds the hub against the rear side of the door. With this construction it will be apparent that by turning the knob or handle 14, the three latch bolts of the latching device may be projected and retracted into and out of latching position, as above described.

The shank of the handle 14 constitutes the cylinder of a pin tumbler lock having the usual pin tumbler chambers 20 on an axially extending key-operated plug 22 mounted therein carrying the pin tumbler sections 23. A set screw 24 is screw-threaded through an aperture in the cylindrical handle shank and the key-operated plug is provided with a slot 26 which receives the inner end of the set screw, the turning movement of the key-operated plug into and out of locking position being limited by engagement of the end walls of the slot 26 with the screw 24. A stud or pin 28 is secured in a socket in the rear end of the key-operated plug by a pin 29, and has its rear end arranged eccentrically to the axis of the plug and received in a transverse notch 30 in a bolt 32, which extends through a transverse aperture in the reduced portion 15 of the handle shank. When the handle is in door latching position, as shown in Figs. 1 and 2, one end of the bolt 32 is arranged opposite a locking notch 34 in the escutcheon so that upon turning the

key-operated plug 22 in a counter-clockwise direction by means of its key, the eccentric pin 28 will act to shift the bolt 32 to position said end thereof in said notch. The end 5 of the bolt substantially fits between the side walls of the notch 34 so that when it is projected therein the handle is securely locked from turning movement and thus the bolts of the three point latching device are held in latching position. To unlock the lock, the key-operated plug is given a quarter turn in the reverse direction, which, through the eccentric pin 28, acts to shift the locking bolt 32 to retract its end from 10 the locking notch 34, whereupon the handle may be turned to release the latch bolts of the three point latching device, and the cabinet door may be opened. When the bolt 32 is thus shifted to disengage its end from 15 the locking notch 34, its other end is projected into an elongated notch or slot 36 in the escutcheon 12. This notch 36 extends beneath a portion of the shoulder 17 and is of suitable length to permit the required 20 quarter turning movement of the handle in a clockwise direction to release the latching device. The end walls of the notch 36 are so positioned that when the handle is turned 25 in a counter-clockwise direction to door latching position, the projecting end of the bolt 32, by engagement with the left hand end wall of the notch 36, accurately limits the movement of the handle to position the 30 other end of the pin opposite the locking notch 34, it being then merely necessary to give the key-operated plug a quarter turn to project the bolt 32 into the locking 35 notch 34 to lock the handle, as above described.

40 It will be apparent that by limiting the turning movement of the handle in locking position in the manner above described, a perfect alinement of the bolt 32 with the recess 34 and the pin tumblers with their 45 chambers is insured which permits the plug to be turned to locking position and the key to be withdrawn so as to leave the door latched. In the embodiment shown, when 50 the handle is turned so that the door is unlatched, the key can not be withdrawn, there being but one set of chambers for the tumblers, and this is the preferred arrangement. When the lock is used in connection with a 55 three point cabinet latching device, as illustrated and described, such limiting of the turning movement of the handle eliminates adjusting and fitting in the assembling to bring the bolts of the latching device into proper position.

60 As will be evident to those skilled in the art, my invention permits various modifications without departing from the spirit thereof or the scope of the appended claims.

What I claim is:

65 1. A lock of the class described having, in

combination, a handle having a shank, a rose in which said shank is mounted for turning movement into and out of a predetermined angular position, a bolt carried by the shank and adapted to be shifted transversely thereof, said rose having a locking notch adapted to receive one end of the bolt when said shank is in said angular position so as to lock the handle from turning movement, and an elongated notch adapted to receive the other end of said bolt when the bolt is out of said locking notch, and key-controllable locking mechanism for shifting said bolt to project the end thereof into and retract it from said locking notch when said shank is in said position.

2. A lock of the class described having, in combination, a handle having a shank, a rose in which said shank is mounted for turning movement into and out of a predetermined angular position, connection between said shank and rose adapted to be controlled to lock the handle from turning movement and to release the handle when said shank is in said predetermined angular position, connection between the shank and rose for preventing turning movement of the shank in one direction beyond said predetermined angular position, but permitting limited turning movement in the opposite direction when said shank is released, and pin tumbler locking mechanism mounted in the handle for controlling said first mentioned connection.

3. A lock of the class described having, in combination, a handle having a shank, a rose in which said shank is mounted for turning movement into and out of a predetermined angular position, a bolt carried by the shank and adapted to be shifted transversely thereof, said rose having a locking notch adapted to receive one end of the bolt when said shank is in said angular position so as to lock the handle from turning movement and having an elongated slot for receiving the other end of the bolt when the bolt is shifted out of said locking notch for preventing turning movement of the shank in one direction beyond said predetermined angular position, but permitting limited turning movement in the opposite direction, and pin tumbler locking mechanism for thus shifting said bolt.

4. A lock of the class described having, in combination, a handle having a shank, a rose in which said shank is mounted for turning movement into and out of a predetermined angular position, a bolt mounted for longitudinal movement in a transverse aperture in said shank, said rose having a locking notch adapted to receive the end of the bolt when said shank is in said angular position so as to lock the handle from turning movement, a pin tumbler lock having its key-operated plug mounted for turning move-

- ment in said shank, and a rearwardly projecting pin mounted on the inner end of said plug eccentrically to its axis, said bolt having a slot for receiving said pin, whereby the bolt may be shifted longitudinally by turning said plug to project the end thereof into and retract it from said locking notch when said shank is in said position.
5. A lock of the class described having, in combination, a handle having a shank, a rose in which said shank is mounted for turning movement into and out of a predetermined angular position, a bolt mounted for longitudinal movement in a transverse aperture in said shank, said rose having a locking notch adapted to receive the end of the bolt when said shank is in said angular position so as to lock the handle from turning movement, and an elongated notch adapted to receive the other end of said bolt when said bolt is out of said locking notch, a pin tumbler lock having its key-operated plug mounted for turning movement in said shank, and a rearwardly projecting pin mounted on the inner end of said plug eccentrically to its axis, said bolt having a slot for receiving said pin whereby the bolt may be shifted longitudinally by turning said plug to project the end thereof into and re-
- tract it from said locking notch when said shank is in said position.
6. A lock of the class described having, in combination, a rose, a handle having a shank extending through said rose and mounted for turning movement therein, a bolt mounted for longitudinal movement in a transverse aperture in said shank, said rose having a locking notch adapted to receive the end of the bolt when said shank is in said angular position so as to lock the handle from turning movement, a pin tumbler lock having its key-operated plug mounted for turning movement in said shank, means for limiting the turning movement of said key-operated plug comprising a screw screw-threaded through said shank and a slot in said plug for receiving the end of said screw, the head of said screw being covered by said rose, and a pin and slot connection between said key-operated plug and said bolt whereby the bolt 50 may be shifted by turning said plug to project the end thereof into and to retract it from said locking notch when said shank is in said angular position.

In testimony whereof, I have signed my name to this specification this 1st day of Aug., 1925.

ERNEST L. TEICH.
